Primary Examiner — Katie Jane Stofko(74) *Attorney, Agent, or Firm* — Fitch, Even, Tabin & Flannery LLP(57) **CLAIM**

The ornamental design for a food product, as shown and described.

DESCRIPTION

FIG. 1 is a perspective view of a food product;
 FIG. 2 is a top plan view of the food product of FIG. 1;
 FIG. 3 is a right side elevation view of the food product of FIG. 1, the left side elevation view being identical thereto;
 FIG. 4 is a front elevation view of the food product of FIG. 1, the rear side elevation view being identical thereto; and,
 FIG. 5 is a bottom plan view of the food product of FIG. 1. The broken line portions of the food product in the drawings are included to show unclaimed subject matter only and form no part of the claimed designs.

The line and stippled shading shown in FIGS. 1-5 represent a contrasting appearance.
